UNITED STATES PATENT OFFICE.

EARL P. MASON, OF NEWPORT, RHODE ISLAND, ASSIGNOR TO THE DRAPER COMPANY, OF PORTLAND, MAINE, AND HOPEDALE, MASSACHUSETTS.

THREAD-PARTER FOR LOOMS.

SPECIFICATION forming part of Letters Patent No. 634,852, dated October 10, 1899.

Application filed May 16, 1899. Serial No. 717,052. (No model.)

To all whom it may concern:

Be it known that I, EARL P. MASON, of Newport, county of Newport, State of Rhode Island, have invented an Improvement in Thread-Parters for Looms, of which the following description, in connection with the accompanying drawings, is a specification, like letters and figures on the drawings representing like parts.

This invention relates to looms provided with automatic filling-supplying mechanism wherein a fresh supply of filling is transferred from a filling-feeder by or through the action of a suitable filling-feeler when the filling has been exhausted to a predetermined extent—such, for instance, as shown in United States Patent No. 600,016, dated March 1, 1898; and the present invention has for its object the parting of the filling closely adjacent the selvage of the cloth just before the ejection of the nearly-exhausted filling-supply and the insertion of the fresh supply of filling.

Various novel features embodied in my invention will be hereinafter described, and particularly pointed out in the following claims.

Figure 1 is a section of a sufficient portion of a loom to be understood, taken transversely to the lay and having one form of my invention embodied therein. Fig. 2 is an enlarged front elevation of a portion of the lay with the thread-parting mechanism mounted thereon. Fig. 3 is a top or plan view thereof. Fig. 4 is a rear elevation thereof, and Fig. 5 is a perspective view of the thread-engaging members detached.

Referring to Fig. 1, the frame A, lay A³, breast-beam A⁴⁰, and actuating or starting rock-shaft d' are and may be all substantially as shown in the patent referred to, the shaft d' being rocked in the direction of arrow 20 by or through the filling-feeler (not shown) to effect the transfer of a fresh supply of filling from the filling-feeder when the previous supply has been exhausted to a predetermined extent.

A dagger or bunter a is secured to the rock-shaft d' by a suitable set-screw 2, the free end of the bunter having a projection a', provided with a convex cam-surface a² on its upper

side for a purpose to be described, rotation of the shaft d' moving the bunter to bring the projection a' at the next forward beat of the lay into position to enter the notch b' in 55 the end of a dog b. The said dog is secured by a set-screw 3 to a shaft c, mounted to rock in bearings d² d³ d⁴, the former two bearings being herein shown as forming part of a casting D, secured to the lay in any suitable manner, as by a bolt 4. A collar c', fast on the shaft c, has attached to it one end of a spring s, the other end thereof being secured to the casting D, the spring normally maintaining the dog b in the position shown, a stop d⁶ on 60 the bearing d⁴ being engaged by a lug b⁶ on the hub of the dog, as herein shown, to limit the movement of the shaft c, due to the spring. When the projection a' enters the notch b', the shaft c is rocked against its spring and 65 elevates the end of an arm e, adjustably secured on the shaft by a suitable set-screw, as 5, the arm having pivoted thereto at e' one end of a longitudinally-adjustable link, shown as comprising a yoke g', connected with the 70 arm e, a threaded rod g, screwed into said yoke at one end, and a second yoke g², screwed onto the other end of the rod g.

The casting D is extended above the lay and at the back thereof, as herein shown, to 80 form a shroud d for the parting members when they are in normal position, the lay being recessed, as at a⁵, (see dotted lines, Figs. 1 and 2,) at the foot of the shroud. A grid m, having, preferably, three slots m', as shown 85 in Fig. 3, is sunk in the lay to lie flush with the shuttle-race adjacent the selvage of the cloth being woven and projecting in front of the shroud at its foot, and the shroud is provided with a cross-pin h⁴, on which are fulcrumed the parting members h and h'. The member h is shown as a blade having its lower end h² bent rearwardly and pivotally connected at h³ between the ends of the yoke g², while the member h' is two-part, its two 95 fingers being arranged at opposite sides of the blade h, with their lower ends bent forward at h⁵ and connected by a pin 6, so that they will rock in unison, a spring s' between the lower oppositely-bent ends of the single and 100 double parting members normally separating their upper ends. The blade h is movable on

its fulcrum in a vertical plane passing through the center slot or depression m' of the grid m , while the fingers of the coöperating member h' are adapted to enter the outer slots of the grid. When the shaft c is rocked, as has been described, the arm e is swung upward and through the adjustable link the parting members h and h' are turned in unison on their common fulcrum until the fingers of the latter member enter the grid-slots and rest upon the lay. As they move down into such position they engage the filling-thread and depress it into the outer slots, holding it taut across the middle slot of the grid, and the continued forward movement of the lay operates thereafter to force the blade or parter h down against the stretched thread, parting it between the fingers h' , which thus serve as downholds for the thread as it is severed, the spring s' stretching as the blade h completes its movement. When this operation has been effected, the movement of the lay brings the lip b^2 of the dog into engagement with the cam-surface a^2 of the bunter a , disengaging the latter from the dog, and thus releasing the rock-shaft c before the lay has completed its forward stroke, the spring s thereof returning the rock-shaft and the thread-parting device to normal position, (shown in the drawings,) so that the parting of the thread and the return of the mechanism to normal position take place before the transfer of fresh filling.

Inasmuch as the automatic filling-changing type of loom herein referred to is so well known and in extended use I have not herein shown any of such filling-changing mechanism, except the controlling shaft d' , thus avoiding multiplication of drawings and description of well-known devices.

My invention is not restricted to the precise construction and arrangement herein shown and described, as the same may be modified or rearranged in various particulars without departing from the spirit and scope of my invention.

Having fully described my invention, what I claim as new, and desire to secure by Letters Patent, is—

50 1. In a loom provided with automatic filling-supplying mechanism, a controller therefor, the lay, means mounted thereon to part the old filling-thread, including a two-part downhold to engage and hold the thread upon the raceway of the lay, and a coöperating member to engage and part the thread between the holding-points, and actuating mechanism to move the downhold into operative position and to thereafter actuate the parting member, operation of the controller effecting the operation of said actuating mechanism.

2. In a loom provided with automatic filling-supplying mechanism, a controller therefor, the lay, a two-part downhold and a coöperating yieldingly-connected thread-parter, both pivotally mounted on the lay and relatively movable, and actuating mechanism to

move the downhold and parter bodily to bring the former into engagement with and to hold the thread at two separated points, continued 70 operation of said mechanism moving the parter independently to part the thread between such points while held, the operation of the actuating mechanism being effected by or through the operation of the controller. 75

3. In a loom provided with automatic filling-supplying mechanism, a controller therefor, the lay, a two-part downhold and a coöperating yieldingly-connected thread-parter between the parts of the downhold, both pivotally mounted on the lay and relatively movable, and mechanism positively connected with the thread-parter, to rock it and the downhold in unison to bring the latter into engagement with the thread, and to thereafter 80 move the parter independently to part the thread between and while held by the two parts of the downhold, operation of the controller effecting the operation of said mechanism. 85

4. In a loom provided with automatic filling-supplying mechanism, a controller therefor actuated by or through partial exhaustion of the filling, the lay, means mounted thereon to part the old filling-thread, said means including a movable two-part downhold and a coöperating parting-blade, and actuating means governed by said controller, to move the downhold into engagement with and to hold the thread upon the raceway of the lay, 90 and to thereafter move the parting-blade to sever the thread while held. 95

5. In a loom, the lay having three transverse recesses in its race adjacent the cloth-selvage, thread-parting means pivotally mounted on the lay, including a two-part downhold and an intermediate parter, a yielding connection between them, mechanism positively connected with the parter, to move it and the downhold in unison until the latter has engaged the thread and entered the outer recesses in the lay, the parter thereafter moving independently to enter the central recess and part the thread stretched across it, and means to effect the operation of said mechanism. 110

6. In a loom, the lay, thread-parting means thereon including a downhold and a coöperating, yieldingly-connected parter, both bodily movable, and mechanism to move the downhold and parter in unison until the former engages the thread, the parter thereafter moving independently to part the thread so held, said mechanism including a dog having a releasing-lip, combined with a bunter adapted to engage and move the dog, a projection on the bunter to be engaged by the releasing-lip when the movement of the dog has been completed, to thereby disengage said dog and bunter, and means to move the 120 bunter into operative position. 125

7. In a loom provided with automatic filling-supplying mechanism, a controller therefor operative upon exhaustion of the filling

to a predetermined extent, the lay, thread-parting means mounted thereon, mechanism to actuate the same, including a dog having a releasing-lip, and a bunter connected with 5 the controller to at times engage the dog and operate said mechanism, forward movement of the lay when said dog and bunter are in engagement operating the parting means, the releasing-lip of the dog acting to disengage 10 the dog and bunter before the lay has com-

pleted its forward movement, whereby the parting means will be actuated before filling transfer.

In testimony whereof I have signed my name to this specification in the presence of 15 two subscribing witnesses.

EARL P. MASON.
